US0D1045373S

(12) **United States Design Patent** (10) **Patent No.:** **US D1,045,373 S**
(45) **Date of Patent:** **** Oct. 8, 2024**

(54) **CASE FOR MECHANICAL PENCIL LEADS**

2,852,160 A	9/1958	Danjczek	
3,648,891 A	3/1972	Katz et al.	
3,794,214 A	2/1974	Kuparinens	
3,815,734 A	6/1974	Krückel	
4,811,842 A	3/1989	Sekiya	
4,984,288 A	1/1991	Petterson	
5,044,805 A	9/1991	Kosteniuk et al.	
D352,524 S *	11/1994	Watanabe	D19/75
5,480,249 A	1/1996	Kageyama et al.	
5,495,938 A	3/1996	Bedford et al.	

(71) Applicant: **MITSUBISHI PENCIL COMPANY, LIMITED**, Tokyo (JP)

(72) Inventor: **Tsuyoshi Nishida**, Tokyo (JP)

(73) Assignee: **MITSUBISHI PENCIL COMPANY, LIMITED**, Tokyo (JP)

(**) Term: **15 Years**

(21) Appl. No.: **29/875,258**

(22) Filed: **May 2, 2023**

Related U.S. Application Data

(62) Division of application No. 35/513,296, filed on Jun. 28, 2021 (U.S. filing date under 35 U.S.C. 384), and having an international filing date of Jun. 28, 2021, now abandoned.

(30) **Foreign Application Priority Data**
